UNITED STATES PATENT OFFICE.

HALBERT M. WOOD, OF NASHVILLE, TENNESSEE.

ADVERTISING-MACHINE.

1,235,408.

Specification of Letters Patent. Patented July 31, 1917.

Application filed May 28, 1915. Serial No. 30,924.

To all whom it may concern:

Be it known that I, HALBERT M. Wood, a citizen of the United States, and a resident of Nashville, in the county of Davidson and 5 State of Tennessee, have made certain new and useful Improvements in Advertising Machines, of which the following is a specification.

My invention relates to improvements in 10 advertising machines, and it consists in the combinations, constructions and arrangements hereinafter described and claimed.

An object of my invention is to provide a 15 device which will automatically bring a series of slides or plates into operative position for projection successively at intervals.

A further object of my invention is to 20 provide a device of the type described comprising an endless chain upon which the plates are suspended with means for moving the chain intermittently, and for stopping the same in its movement when the plates have been brought into operative position, and for again starting the movement 25 of the machine so as to bring another plate in a position for projection.

A further object of my invention is to 30 provide a device of the type described in which means is provided for starting the operation of the device at any predetermined time and for stopping the device at any other predetermined time.

A further object of my invention is to 35 provide novel means for effecting the intermittent operation of the endless chain, so that the plates or slides may be quickly shifted from one position to another and allowed to remain a sufficient length of time for projection and for permitting the removal 40 of plates or slides and the substitution of other plates or slides during the interval of rest.

Other objects and advantages will appear 45 in the following specification, and the novel features of the invention will be particularly pointed out in the appended claims.

My invention is illustrated in the accompanying drawings forming part of this application, in which,

50 Figure 1 is a perspective view of the device, one of the side doors of the device being open to show the interior mechanism.

Fig. 2 is a diagrammatic view of the electric circuits.

55 Fig. 3 is a vertical section through the device.

Fig. 4 is an enlarged detailed view of the starting and stopping means.

Fig. 5 is a perspective view showing the means of attaching a slide holder to the 60 endless chain.

Fig. 6 is a section on the line 6—6 of Fig. 3.

Fig. 7 is a detailed view showing a portion of the actuating mechanism. 65

Fig. 8 is a view similar to Fig. 7 showing the actuating mechanism in a different position, and,

Fig. 9 is a view showing the actuating mechanism in a third position. 70

In carrying out my invention I provide a casing or cabinet 1, which is provided with legs 2 so as to raise the cabinet from the floor. On the opposite side of the cabinet are doors, such as those shown at 3 and 75 4, respectively, these doors being preferably of such extent as to expose the interior of the cabinet from top to bottom, in order to permit access to the parts contained therein. At the top of the cabinet is a hinged cover 80 5, which is arched so as to accommodate a portion of the interior mechanism.

Horizontal partitions 6 and 7 are provided which extend across the cabinet, and which divide the latter into an upper compartment, a central compartment and a lower bottomless compartment. Between the partition 6 and the upper frame members 8 of the cabinet are uprights 9, whose purpose 85 will be explained later.

Secured to the front portion of the cabinet or casing is a cross member 10 upon which are mounted forwardly projecting guide rods 11 for the bellows-frame 12, the latter bearing a lens tube 13. This bellows 95 is arranged to register with an opening 1* in the front of the casing 1, as shown in Fig. 3.

Disposed within the interior of the casing 1 is the lamp house 14. Secured to the front portion thereof is the compound lens 15. 100 For projecting purposes I prefer to use an electric light, and this light is shown at 16, the same being held in the bottom of the lamp house as shown in Fig. 3.

In order to support the plates I provide 105 an endless carrier which comprises a shaft 17 upon which are mounted the two sprocket wheels 18 and 19. The ends of the shaft 17 are journaled in the uprights 9—see Fig. 6. The shaft 17 is provided with a ratchet 110 20, while loosely mounted on the shaft 17 is a sleeve 21 bearing an arm 22 to which

is secured a spring pressed pawl 23. To the arm 22 is pivotally connected a lift rod 24 bearing at its bottom a cam roller 25.

Arranged to run over the sprocket wheels 5 18 and 19 are sprocket chains 18^a and 19^b respectively. These sprocket chains are connected at intervals by means of transverse rods 26 having spacing members 27 for holding the chains in spaced relation.

10 Suspended from each of the rods is a frame for holding an individual slide or plate, this frame being indicated at 28 in Fig. 5. The frame is provided with a groove 29 arranged to receive a plate 30, the groove 29 extending through the side of the frame so as to permit entrance to the plate in the manner clearly shown in Fig. 5.

Hooks 31 suspend the plate from the rod 26 so that in the movement of the endless 20 chain the plate remains substantially in vertical position. As will be clearly seen from Figs. 5 and 6, the plates have room to pass between the sprocket wheels 18 and 19.

Referring to Figs. 7, 8 and 9, it will be 25 seen that the lift rod 24 is provided with a stopping member 32 carried upon laterally extending posts or pins 33. This stop member is arranged to be engaged by arms 34 which extend laterally from the sprocket 30 wheel 18, as will be hereinafter explained.

Carried by the partition 7 is an electric motor M, whose shaft is provided with a pulley 34 which is connected by a belt 35 with a pulley 36 on a shaft 37. The latter 35 bears a small pulley 38 which is connected by a belt 39 with a pulley 40 on a shaft 41 bearing a worm 42 arranged to engage a worm 43, on a shaft 44. The latter bears a cam 45 which is arranged to engage the 40 cam roller 25 so as to cause a movement of the latter during the operation of the motor M. From this arrangement it will be seen that the time of rotation of the shaft 44 is much greater than that of the motor 45 M. As will be seen from Fig. 6 a spiral spring 46 is secured at one end to the bottom of the lift rod 24 and at the other end to the partition 7. When the lift rod is moved upwardly tension is exerted on the 50 spring 46.

On the inside of the casing is arranged a guide member 47 which may be of sheet metal. The top of this guide member is bent inward as shown in Fig. 3 and it extends downwardly parallel to the outer wall 55 of the casing 1 and then inwardly and upwardly parallel to the opposite wall of the casing and at the top is curved upwardly and inwardly. This guide member serves not only as a means of guiding the frames 60 which carry the plates, but the bottom part forms a protecting medium so as to prevent any oil which might drop down, from dropping on the carrier frames and injuring 65 the plates carried thereby.

In order to render the device completely automatic, I provide a starting and stopping mechanism. These mechanisms are composed of a pair of ordinary alarm 70 clocks.

In Figs. 1 and 4 it will be seen that there is a clock 48 and a similar clock 49. One of these is used as a starting device and the other as a stopping device. In explaining the action of the starting and stopping device, one should first consider the electrical connections. In Fig. 2 the lead wires are shown at 50 and 51 respectively. A light 52 is arranged in a branch circuit connected to these lead wires. This light 52 is for 80 the purpose of illuminating the faces of these clocks.

A motor M is connected with the lead wires 51 by means of a switch S, and in parallel with the motor is the lamp 16. The switch S may be of any suitable nature, but is preferably of that type of snap switch in which the pull on a flexible member will cause the switch to alternately open and close the circuit.

In order to effect this pull automatically, I provide the winding key stems 48^a and 49^b with laterally extending arms 48^b and 49^a, these arms being in turn provided with pins like that shown at 52 in Fig. 6, to which 95 are loosely connected links or swivels 53. Chains 54 connect the swivels 53 and the ring 55, which is passed over the hooked end 56 of a spring 57. The opposite end of the spring is attached to a flexible member 57, which in this instance consists of a ball 100 strung upon a flexible cable or wire, this string of balls passing over a pulley 58 and then entering the casing of the switch S so that when the flexible member 57 is 105 pulled it will cause the action of the switch in a well known manner.

From the foregoing description of the various parts of the device the operation thereof may be readily understood.

Let us assume that the operator wishes to project the pictures on a screen at the top of a building continuously from the hours of seven to eleven o'clock p. m. He first disconnects the ring 55 (see Fig. 4) 115 from the spring 56 and then after setting the alarms on the starting clock 49 and the stopping lock 48 to operate at seven and eleven o'clock p. m. respectively, he winds the alarm one revolution, or until the arms 120 48^a and 49^b strike the stop members 48^c and 49^c, which are secured to the under side of the partition 7. He now attaches the ring 55 to the hooked portion 56^a of the spring 56.

The slides are inserted in the carriers and the apparatus is now ready for operation. At seven o'clock the alarm mechanism will start to operate and this will cause a pull on the chain which is connected with the switch S, sending current to the light 16 130

and also to the motor M. The revolution of the latter will cause the rotation of the cam shaft 44 and therefore of the cam 45. In Fig. 6 the cam roller 25 is shown in its lowest position, *i. e.*, in that position in which a slide for a plate 30 is immediately in front of the lens 15 and therefore in position to be projected upon a screen 59.

As the motor continues to revolve the cam 45 will be moved from the position shown in Fig. 7 to that shown in Fig. 8 and this will cause the lift rod 24 to lift the arm 22 so as to bring the pawl 23 into position to engage another tooth on the ratchet 20. As soon, however, as the cam passes its position shown in Fig. 8, the spring 46 pulls downwardly on the arm 22, thereby causing the pawl 23 to engage the ratchet 20 and to turn the sprocket wheels so as to cause a movement of the endless chains and the shifting of the carriers. In order to limit this downward movement and to stop the carriers at a point which will bring one of the plates in registration with the opening 25 1⁸. I provide the stop arms 34 on the wheel 18, as before stated, these stop arms engaging the stop member 32. On the next upward movement of the lift rod 24, the stop member 32 is moved out of the path of the 30 arm or pin 34, thus permitting the revolution of the sprocket wheel. It will be seen that the plates will be moved intermittently. If it is desirable to change the plates during the operation of the device this can be 35 done very readily, because the period of rest while the picture or inscription is projected is of sufficient duration to enable the operator to insert a slide or plate in the carrier 28 in a manner shown in Fig. 1.

40 Now when the time arrives for the closing of the exhibition the alarm mechanism of the stopping clock 48 will be operated, and this will cause a pull on the chain, which is connected with the switch S, thus 45 cutting off the current from the light 16.

It will be seen that I have provided a device by means of which pictures or advertising matter of any kind may be projected in succession for a predetermined period 50 without the necessity of the attendance of an operator.

The device is compact and takes up a comparatively small space and is not liable to easily get out of order.

55 I am aware that other devices based on the same general plan might be constructed, but I consider as my own, all modifications as fairly fall within the spirit and the scope of the invention.

60 I claim:—

1. In an advertising device, a casing provided with a light opening, a shaft jour-

naled in said casing, a pair of sprocket wheels carried by said shaft, a chain for each sprocket wheel, means connecting said chains together, a series of plate bearing frames pivotally suspended from said chain connecting means, means for guiding said frames past said light opening, and means carried within said guiding means for intermittently operating said shaft.

2. In an advertising device, a casing provided with a light opening, a shaft journaled in said casing, a pair of sprocket wheels carried by said shaft, a chain for each sprocket wheel, means connecting said chains together, a series of plate bearing frames pivotally suspended from said chain connecting means, means for guiding said frames past said light opening, means for intermittently operating said shaft and means for stopping the movement of said shaft when one of the plates is in exact registration with said opening, said intermittent operating means and said stopping means being disposed within said guiding means.

3. In an advertising device, a casing provided with a light opening, an endless carrier arranged for movement in a vertical direction, a series of plate bearing frames pivotally suspended from said endless carrier, a guide member comprising a U-shaped plate having one portion disposed near the front wall of the casing and another portion disposed near the rear wall, the space between the guide member and the casing walls forming front and rear guideways for said plate bearing frames, and means disposed within said U-shaped guide member for intermittently operating the endless carrier.

4. In an advertising device, a casing provided with a light opening, an endless carrier, a series of plate bearing frames pivotally suspended from said endless carrier, a U-shaped guide member coöperating with the front wall of said casing for guiding said pivoted plate bearing frames, the upper portion of said guide member being curved, whereby the lower edge of the pivoted frames are guided successively into the space between the guide member and the front wall of the casing, and means disposed within the U-shaped guide member for intermittently moving said endless carrier and for causing the stopping of the latter when a plate is in registration with the light opening.

HALBERT M. WOOD.
